UNITED STATES PATENT OFFICE

1,940,191

OPENING AND CLOSING DEVICE FOR CAR DOORS

John H. Simonton, Brighton, Tenn., assignor of forty-nine percent to Charles Pressley Simonton and Charles B. Simonton, both of Covington, Tenn.

Application December 12, 1929
Serial No. 413,601

1 Claim. (Cl. 268—44)

The object of this invention is to provide novel means for operating a door.

In the accompanying drawing:

Figure 1 is an elevation showing a device constructed in accordance with the invention;

Figure 2 is a section on the line 2—2 of Figure 1;

Figure 3 is a section on the line 3—3 of Figure 1.

10 In the drawing, the numeral 63 designates any structure on which a sliding door may be used. A lower track 64 and an upper track 65 are shown. Striking posts appear at 66 and 67, and retaining fingers on the post 66 are shown at

15 68, the door 69 engaging behind the fingers when the door is closed. A latch mechanism 70 for the door 69 is provided. The upper edge of the door 69 is slidably engaged with the upper track 65. Wheels 71 are located in recesses 72

20 in the door 69 and are journaled at 73 on the door. The wheels 71 roll in a groove 74 in the lower track 64. A rack or track 75 is secured in a groove in the upper edge of the lower track 64. An eccentric 76 is journaled in the door 69.

25 A shaft 77 is mounted to turn in the eccentric 76. The shaft 77 carries a crank 78, or other operating means, at its outer end. A pinion 79 is secured to the inner end of the shaft 77 and is located in a recess 80 formed in the rear side

30 of the door 69. On its forward end, the eccentric 76 has an enlarged disc-like head 81. The head 81 overlaps the outer surface of the door 69 and the pinion 79 overlaps the inner surface of the door, and, thus, the eccentric 76 is held for

35

rotation in the door. The pinion 79 meshes with the rack or track 75. The head 81 of the eccentric 76 is provided with a handle 82 having resiliency enough so that it can be engaged in, and disengaged from, seats 83 and 84 formed in 60 a curved keeper plate 85 on the door 69.

When the handle 82 on the eccentric 76 is engaged in the seat 84, the pinion 79 is engaged with the rack or track 75. The shaft 77 can be turned by means of the crank 78, and when 65 the shaft is turned, the door 69 can be slid to the right or to the left, because the pinion 79 on the shaft 77 is engaged with the rack or track 75.

In the event that it is desired to shift the 70 pinion 79 out of engagement with the rack or track 75, so that the door 69 can be slid quickly, by the application of considerable force, this can be done by engaging the handle 82 in the seat 83. When the handle 82 is shifted from 75 the seat 84 to the seat 83, the eccentric 76 is rotated, the shaft 77 being lifted, and the pinion 77 disengaged from the rack or track 75.

What is claimed is:—

In a device of the class described, a structure 80 having a doorway, a door for the doorway, means for mounting the door slidably on said structure, an eccentric journaled in the door, a lever connected to the eccentric, means on the door for holding the lever in adjusted positions, a rack 85 carried by the said structure, a shaft journaled in the eccentric, and a pinion carried by the shaft and meshing with the rack.

JOHN H. SIMONTON.
